VACUUM CLEANER

Benjamin D. Goldberg, Brooklyn, N. Y.

Application July 15, 1936, Serial No. 90,649

18 Claims. (Cl. 15—14)

This invention relates to vacuum cleaners and has for its object to increase their convenience and salability without increasing the cost or impairing the efficiency of such a device.

5 In devices of this class intended to serve either as a blower or as a cleaner, it has been difficult to construct an airtight valve or shutter to control the discharge of air in either of two directions from the fan casing without the expense 10 of a precision fitting to stop the flow of air out of the casing in any other than the desired direction.

Another object of this invention is to provide a simple means, opening the suction chamber for 15 access to brush, belt and pulley, without projections on the closure.

According to this invention such air leakage is eliminated by providing the shutter with radially or normal integral walls which form an 20 air-tight enclosure without the necessity of having such expensive precision fitting to prevent air leakage around the shutter. In doing so, the interior of the fan casing is maintained clear 25 of any screw or bolt heads around which dust and dirt might collect and be blown out when not intended. The exterior of the device is made attractive in appearance and free from slots or any screws on the sides of the casing as have been heretofore suggested.

Referring to the drawings:

30 Fig. 1 is a side elevation partly in section of a vacuum cleaner embodying the present invention.

Fig. 2 is a section on the line 2—2 of Fig. 1.

35 Fig. 3 is a section on the line 3—3 of Fig. 2.

Fig. 4 is a perspective of a fragment of the shutter.

40 Fig. 5 is a perspective of the actuating knob for shifting the shutter and a portion of the ring to which it is attached.

Fig. 6 is a section through a modified construction of the shutter.

Fig. 7 is a bottom plan view of the device of Fig. 1.

45 Fig. 8 is a section on the line 8—8 of Fig. 7.

Fig. 9 is a section on the line 9—9 of Fig. 7.

Fig. 10 is an exploded view of parts of the vacuum cleaner and casing embodying the present invention.

50 Fig. 11 is a top plan view of the device shown in Fig. 6.

Referring to the drawings, as shown in Fig. 1, there is provided a casing 100 for housing a rotating fan 101 driven by a motor housed within the casing 102. Supply leads 103 carry current

to the motor and a switch 104 opens and closes the motor circuit. Beneath the casing 100 is a suction chamber 105 containing the rotating brush 106 located over the suction opening 107 and driven by the belt 109 passing around the 5 pulley 108 on the motor and fan shaft. At the front of the casing is located an air passage nozzle 110 which extends over the suction chamber. Substantially diametrically opposite to the air discharge nozzle 110 is a second air discharge 10 nozzle or passage 111. Each of these air discharge nozzles or passages is controlled by the shutter 112 whereby air may be discharged either out of the front nozzle 110, or when that is closed, such air may be discharged rearwardly through 15 the handle 113 to the dust bag 114 which is removably attached to the supporting handle 113.

The shutter 112 includes a peripheral portion connecting two radial walls 115 and 116 normal to the shutter and fan axis, which are substantially integral with the peripheral portion of the shutter and extend inwardly beyond the periphery of the fan 101. A projection 117 engaged in substantially the plane of one of the walls 115 constitutes a part of the actuator for angularly shifting the shutter. The casing 100 has an open slot 118 formed therein as shown in Figs. 2 and 10 and surrounding this slot is a ledge 119 on which the actuating ring 120 may be held.

The ring 120 is provided with a notch 121 to receive the projection 117 and the ring also has a projecting portion 122 serving as a handle by means of which the ring and the shutter may be moved together. In the position shown in Fig. 2 the actuating handle 122 and the shutter are 35 in a position such that the air discharge nozzle 110 is closed whereas the rear air discharge nozzle is open with the result that air is sucked in through the opening 107 and is thence directed rearwardly into the bag 114. If the ring 120 is 40 shifted angularly to a position such that the projection 117 is substantially contiguous the opposite end of the slot 118, then the shutter will be in a position closing the rear air discharge nozzle 111 and opening the front nozzle 110. 45

A feature of this invention is the provision of the ring 120 which is so proportioned as to close the peripheral opening of the slot 118. The slot 118 is closed on top by the flange of the motor casing.

The wall 115 adjacent the motor is provided with a flange or ridge 123 close to the rotating blades of the fan, such a ridge being customary and well known in this art for the purpose of preventing dust particles getting in between the 55

fan and the upper wall 115. The casing 100 is provided with an intake opening 124 between the suction chamber 105 and the fan. A washer of felt or other appropriate material 128 extends around the opening 124 to provide a seal between the casing and the wall 116 of the shutter.

Another washer 128 of similar material is located around the fan shaft and within a recess provided in the top wall 115, to also provide better sealing against air leakage. Screws 127 secure the base flange of the motor casing onto the casing 100 enclosing the fan.

Instead of having the top wall in one part as shown in Figs. 3, 4 and 10, a modified construction is illustrated in Fig. 6 in which the integral portion of the wall 115a extends inwardly only a short distance and is then provided with a removable portion 128 supported as shown in Fig. 6 on a stepped flange. Having the cover portion 128 removable permits the fan 101 to be inserted through the opening on removal of the cover 128, whereas in Figs. 2, 3 and 10, for example, the fan 101 is inserted into the shutter through the peripheral opening 130 indicated in Figs. 2 and 10. The removable cover 128 is provided with a projection 137 fitting in a corresponding recess in the wall 115a so that the removable cover may be angularly adjustable with the shutter. In both embodiments illustrated in Figs. 3 and 6 there is an opening 129 or 129a over the casing opening 124 through which the incoming air passes. The ledge 138 constitutes the support for the removable cover 128. In Fig. 6 the parts corresponding to those recited in the embodiment illustrated in Figs. 3 and 10, are in Fig. 6 designated with the same reference numeral with the addition of the letter *a*.

On the bottom of chamber 105 are closure sections 131 and 134. Section 131 is located on the side where the brush is, and covers part of the opening. Section 134 is located adjacent the pulley and covers the balance of the suction chamber. A lap-under portion 133 of section 131 holds this section closed. Figs 8 and 9 show this construction and illustrate the use of a spring 136 secured to the section 134 and engaging the underside of a flange in the body portion of the casing for frictionally holding the section 134 in position.

Some of the features of this invention include the provision of the shutter with integral normal or radial plates. The fan may be inserted from the side or through the top by means of the removable cover 128. The peripheral opening 130 in the shutter is of such angular extent as to open or close either opening but not open or close both at the same time to the full extent. The shutter is actuated on the left side of the casing so that the device may be held with the right hand grasping the handle 113 and the left hand used to adjust the shutter and also the stopping and starting of the motor by means of the switch 104. The actuating projection 117 is substantially opposite the peripheral opening 130. The peripheral opening 118 in the casing is closed by a ring. The washers 125 and 126 stop any tendency for air leakage.

As shown in Figs. 1 and 3 the air passage from the fan through either the front or rear passage 110 or 111, are free from dead air spaces into which dust or dirt might collect, the walls of these passages being slightly rounded as shown in the drawings. This rounding of the entrance to these air passages will be seen from Figs. 2 and 3 to occur both in the vertical and the horizontal

planes, that in the vertical plane as shown in Fig. 3 being useful to eliminate any dead air spaces while that in Fig. 2, especially on one side, is useful in directing the whirling air into the discharge nozzle. This device when used as a blower, may also be used as an atomizer or to blow powdered or granular material for fumigating purposes, or for preservation of goods against moths. The absence of any screw heads or other projections on the inside of the fan casing which might be of a nature to cause dust or dirt to collect, has been of advantage in this invention. The presence of the projection 137 on the removable cover 128 prevents any tendency for the removable cover to slip relative to the shutter, and the absence of any relative movement between the shutter and the removable cover 128 makes possible a better and more air tight joint between them.

The peripheral portion of the shutter 112 may be soldered or welded to the walls 115 and 116, or these parts may be constructed substantially integral or the connection between them made in such manner as to preclude air leakage between the casing and shutter in any other convenient manner.

The projection 117 may be a part of the wall 115 and where the wall 115 is stamped out of sheet metal and later soldered or welded to the peripheral wall 112, the projection 117 is likewise stamped out at the same time.

In the embodiment shown in Fig. 10 the parts are assembled in the following manner. The fan is inserted in the peripheral opening 130 of the shutter. The shutter with the fan inside is then mounted upon the motor shaft by the clamping action of the integral nut and pulley 108, or the motor shaft may be made splined or non-circular in cross section. The motor casing with attached shutter and fan may then be inserted into the casing 100. Before doing so however, the washer 128 is laid between the wall 116 and the top of the suction chamber around the opening 124, and the opposite felt washer 126 is put in place in the recess shown in the wall 115. Also before the motor and shutter have been put in place the ring 120 is preferably mounted on the ledge 119 so that when the projection 117 extends out of the opening 118 it may be received within the recesses 121 of the ring 120.

In the embodiment shown in Fig. 6 the shutter and its walls may be inserted in the casing 100 before the fan and motor have been mounted, since here the wall 128 is removable to permit insertion of the fan after the shutter is in place.

Another advantage of the present invention is the elimination of any projection extending either longitudinally or laterally beyond the walls of the suction chamber, since it has been found such a projection may catch on the clothing or some other obstacle.

From Figs. 7 to 9 inclusive it will be seen that according to this invention there is no such objectionable projection and the rear portion of the plate 133 is held closed by the plate 134, the plate 134 being adapted to move rearwardly to release or open the plate 133, so that the plates 133 and 134 are movable in opposite directions to open the suction chamber.

Instead of having the projection 117 of the shutter engaged in recess 121 of ring and using projection 122 for actuating the shutter, projection 117 of shutter may be prolonged to pass over the ring 120 and act as an actuator. In this case projection 122 of said ring will not

be necessary. The packing strips 125 or 126 might, if desired, be located closer to the periphery of the shutter instead of in the positions indicated. When the front discharge opening 110 is connected with a liquid spray device, it has been found that at times reduction of the pressure through the nozzle 110 by moving the shutter 112 to partially close the nozzle 110 and partially open the opposite nozzle 111, may be 10 desirable.

I claim:

1. In a vacuum cleaner comprising a casing, a fan within the casing, and a pair of air discharge passages from said casing, a curved shutter between said casing and fan for opening one and closing the other of said passages, said shutter having a peripheral open portion contiguous the casing and also walls on both sides of the fan substantially normal to the fan axis and movable with and forming an air tight connection with the peripheral portion of the shutter to stop any air leakage between the shutter and casing.

2. In a vacuum cleaner comprising a casing, a fan within the casing, and a pair of air discharge passages from said casing, a curved shutter between said casing and fan for opening one and closing the other of said passages, said shutter having a peripheral open portion contiguous the casing and also walls substantially normal to the shutter and movable with and forming an air tight connection with the peripheral portion of the shutter to stop the tendency of any air to leak over a curved peripheral edge of the shutter, said normal walls extending inwardly of the fan periphery on each side, and the peripheral portion of the shutter being angularly open to allow insertion and removal of the fan within the shutter when the same is removed 40 from the casing.

3. In a vacuum cleaner comprising a casing, a fan within the casing, and a pair of air discharge passages from said casing, a curved shutter between said casing and fan for opening one and closing the other of said passages, said shutter having a peripheral open portion contiguous the casing and also walls substantially normal to the shutter and movable with and forming an air tight connection with the peripheral portion of the shutter to stop the tendency of any air to leak over a curved peripheral edge of the shutter adjacent any of said passages, said normal walls extending inwardly and one of them being provided with a removable portion through 55 which the fan may be inserted and removed from the casing.

4. In a vacuum cleaner comprising a casing, a fan within the casing, and a pair of air discharge passages from said casing, a curved shutter between said casing and fan for opening one and closing the other of said passages, said shutter having a peripheral open portion contiguous the casing, an actuator for the shutter extending through a casing wall, said casing being provided 60 with a slot through which said actuator extends, and an arcuate closure for said slot on the outside thereof.

5. In a vacuum cleaner comprising a casing, a fan within the casing, and a pair of air discharge passages from said casing, a curved shutter between said casing and fan for opening one and closing the other of said passages, said shutter having a peripheral open portion contiguous the casing, an actuator for the shutter extending 70 through a casing wall, said casing wall being pro-

vided with a slot through which said actuator extends, and a ring surrounding said casing and closing said slot said casing outer wall having a groove in which said ring is held.

6. In a vacuum cleaner comprising a casing, a fan within the casing, and a pair of air discharge passages from said casing, a curved shutter between said casing and fan for opening one and closing the other of said passages, said shutter having a peripheral open portion contiguous the 10 casing, an actuator for the shutter passing through a side wall of the casing, said casing side wall being provided with a slot through which said actuator extends, and a ring surrounding said casing and closing said slot said casing outer 15 wall having a groove in which said ring is held, a handle projecting outwardly from said ring, and a removable side for said casing constituting a side wall of said groove and holding said ring in place.

7. In a vacuum cleaner comprising a casing, a fan within the casing, and a pair of air discharge passages from said casing, a curved shutter between said casing and fan for opening one and closing the other of said passages, said shutter having a peripheral open portion contiguous the 25 casing and an inwardly extending wall substantially normal to the shutter and on each side of said fan integral with said shutter, one of said normal walls being substantially contiguous a 30 permanent closed side of said casing and the other of said walls being adjacent a removable side wall for said casing.

8. In a vacuum cleaner comprising a casing, a fan within the casing, and a pair of air discharge 35 passages from said casing, a curved shutter between said casing and fan for opening one and closing the other of said passages, said shutter having a peripheral open portion contiguous the casing and an inwardly extending wall substantially normal to the shutter on each side of said fan and integral with said shutter, one of said normal walls being substantially contiguous a permanent closed side of said casing and the other of said normal walls being adjacent a removable side 45 wall for said casing, one of the normal walls engaging an actuator for said shutter, said casing being provided with a slot in which said actuator is adapted to be moved.

9. In a vacuum cleaner comprising a casing, a fan within the casing, and a pair of air discharge 50 passages from said casing, a curved shutter between said casing and fan for opening one and closing the other of said passages, said shutter having a peripheral open portion contiguous the 55 casing, an arcuate closure movable around the outside of said casing for an arcuate slot therein, said arcuate closure being connected with said shutter for shifting with the same, and an actuating handle for moving both the shutter and 60 arcuate closure.

10. In a vacuum cleaner comprising a casing, a fan within the casing, and a pair of air discharge 65 passages from said casing, a curved shutter between said casing and fan for opening one and closing the other of said passages, said shutter having a peripheral open portion contiguous the casing and an inwardly extending wall substantially normal to the fan axis on each side of said fan integral with said shutter, one of said normal 70 walls being substantially contiguous a permanent closed side of said casing and the other of said normal walls being adjacent a removable side wall for said casing, one of the normal walls extending outwardly for a short angular distance to 75

constitute an actuator for said shutter, said casing being provided with a slot in which said actuator is adapted to be moved, said actuator being located substantially opposite the open portion of 5 said shutter.

11. In a vacuum cleaner comprising a casing, a fan within the casing, and a pair of air discharge passages from said casing, a curved shutter between said casing and fan for opening one and 10 closing the other of said passages, said shutter having a peripheral open portion contiguous the casing, a suction chamber below said casing, said suction chamber being formed with a brush space, a motor above the casing, the bottom of said casing 15 being open to receive air taken in through said suction chamber, said shutter having walls substantially normal thereto on each side of said fan, a washer between said shutter normal wall and casing bottom, a cover closing said casing on top, 20 a shaft extending from said motor through said cover and top normal wall and on which said fan is supported, and a washer adjacent said shaft and between said cover and top normal wall.

12. In a vacuum cleaner comprising a casing, 25 a fan therein, a suction chamber below the fan and through which air is drawn by said fan, an air discharge nozzle extending forwardly from the casing over said nozzle, and another air discharge nozzle extending rearwardly from said 30 casing and leading to a dust bag, a curved shutter within the casing for opening either of said nozzles and closing the other to the discharge of air, a motor and motor casing closing the top of said casing, a ring for actuating said shutter, 35 said ring being located on the outside of said casing and resting on a shoulder formed on the outer casing wall, said ring extending over each of said nozzles.

13. In a vacuum cleaner comprising a casing, a 40 fan within the casing, and a pair of air discharge passages from said casing, a curved shutter between said casing and fan for opening one and closing the other of said passages, said shutter having a peripheral open portion contiguous 45 the casing and also walls substantially normal to the fan axis movable with and forming an air tight connection with the peripheral portion of the shutter to stop the tendency of any air to leak over a curved peripheral edge of the shutter adjacent any of said passages, said normal walls extending inwardly of the fan periphery on each 50 side, and the peripheral portion of the shutter being angularly open to allow insertion and removal of the fan within the shutter when the 55 same is removed from the casing, a ridge on at least one of said normal walls spaced from the peripheral portions of said shutter and lying substantially adjacent the periphery of said fan.

14. In a vacuum cleaner comprising a casing, 60 a fan therein, a suction chamber below the casing, an air discharge nozzle extending forwardly from the casing over said suction chamber, and another air discharge nozzle extending from the casing rearwardly for connection to a dust bag, 65 a curved shutter between the fan and casing for opening either of said nozzles and closing the other, means for preventing leakage of air around the curved edges of said shutter which includes inwardly extending walls substantially normal to the fan axis on opposite sides of the fan and 70 movable and integral with said shutter, an ac-

tuator for the shutter engaged in substantially the plane of the upper one of said normal walls, a slot in the casing in which said actuator is movable, a ring constructed as a part of said actuator, closing said slot and passing above both 5 of said nozzles and a handle on said ring for angularly shifting said ring, shutter and normal walls.

15. In a vacuum cleaner comprising a casing, a fan therein, and angularly spaced air discharge 10 nozzles leading from said casing, a curved shutter within said casing and around the fan for opening one and closing the other of said air discharge nozzles, a wall substantially normal 15 to the shutter extending inwardly on each side of said fan and secured to the peripheral edges of said shutter with a substantially airtight connection, an actuator engaging with said shutter in substantially the plane of one of said normal walls, the casing being provided with a peripheral 20 slot open on the side of the casing and a removable wall for closing the open side of said slot.

16. In a vacuum cleaner comprising a casing, 25 a fan therein, and angularly spaced air discharge nozzles leading from said casing, a curved shutter within said casing and around the fan for opening one and closing the other of said air discharge nozzles, said shutter including walls substantially normal thereto on each side of said 30 fan, said shutter having an opening which is as long longitudinally of the fan axis as the distance between the normal walls on each side of said fan whereby no dead air pockets are formed in the peripheral corners of said casing adjacent the shutter and in which dust and dirt might collect 35 when the air is being blown out one nozzle and be blown out the other when the shutter has been shifted.

17. In a casing for a vacuum cleaner comprising oppositely directed discharge nozzles, curved 40 walls adapted to surround a fan, a wall substantially normal to the fan axis below the space for a fan, a suction chamber below said normal wall, another normal wall above the fan space, an arcuate groove in the upper edge of the curved wall 45 of the casing between said nozzles, an arcuate shutter having walls substantially normal to the fan axis within the casing for opening one and closing the other of said nozzles, an actuating handle for said shutter extending out of said arcuate groove, and said slot being closed by the second mentioned normal wall.

18. In a casing for a vacuum cleaner comprising oppositely directed discharge nozzles, curved 50 walls adapted to surround a fan, a wall substantially normal to the fan axis below the space for a fan, a suction chamber below said normal wall, another normal wall above the fan space, an arcuate slot in the curved wall of the casing between said nozzles, a shutter within the casing 55 for opening one and closing the other of said nozzles, said slot being closed on top by the second mentioned normal wall, a ledge around said casing above said nozzles, and below the top of said arcuate slot, a ring supported on said ledge, and a handle on said ring movable with said shutter for actuating the same, said second mentioned normal wall extending over said ring to hold the same in place.

BENJAMIN D. GOLDBERG.

70
